UNITED STATES PATENT OFFICE

160,972

BONNET

John R. Robbins, San Antonio, Tex., assignor to
Maxie A. Hill, San Antonio, Tex.

Application January 23, 1950, Serial No. 7,406

Term of patent 14 years

(Cl. D3—13)

To all whom it may concern:

Be it known that I, John R. Robbins, a citizen of the United States, residing at San Antonio, in the county of Bexar and State of Texas, have invented a new, original, and ornamental Design for a Bonnet, of which the following is a specification, reference being had to the accompanying drawing, forming part thereof.

Figure 1 is a plan view of a bonnet, showing my new design as it appears in a flattened position;

Figure 2 is a side elevational view thereof as it appears in a wearing position; and

Figure 3 is a rear elevational view thereof.

I claim:

The ornamental design for a bonnet, as shown.
JOHN R. ROBBINS.
